UNITED STATES PATENT OFFICE

ABRAHAM M. DELLINGER, OF LANCASTER, PENNSYLVANIA

GEAR MECHANISM

Application filed October 29, 1928. Serial No. 315,815.

This invention relates to speed reducing mechanism primarily intended for use in hammer-type grinding mills such as now in extensive use on farms for grinding grain, hay, vines, stems and other suitable farm produce in the preparation of ground and mixed stock, poultry, etc., feeds, and in such use is driven from the rotor shaft and interposed in the driving connections between 5 said shaft and the usual feed rolls to reduce the speed of the feed rolls to suitable limits in comparison with the rotor, which is usually driven in such type of mills at a speed 10 ranging between 2,000 to 2,400 rotations per minute.

The primary objects of the present invention are, to provide simple manually adjustable means for positively selectively varying 20 the speed of rotation of said feed rolls over a wide range between a maximum speed of say 35 rotations per minute and a minimum speed of say 5 rotations per minute, whereby the rate of feed of the material being operated upon may be very definitely 25 and closely regulated in accordance with the nature of such material and the capacity of the power plant; to provide such a reduction gear in which the parts may be moved to change the speed of said feed rolls without stopping, or modifying the speed of rotation of, the hammer rotor during such 30 adjustment; to provide in such a reduction gear a novel combination of two parallel 35 shafts, a plurality of gears of progressively increasing diameter keyed to one of said shafts, a gear keyed to the other shaft, and means partially rotatable about the latter gear and adjustable for selectively establishing 40 driving connection between the same and any one of said plurality of gears; to provide simple means for locking said combination of gears in driving engagement; and to provide simple means for positively preventing 45 misalignment of the gears during adjustment from one selective speed to another, all as hereinafter more particularly set forth, described and claimed.

It may be well to observe that with a given 50 capacity of power plant some materials to be ground, for instance oats, should be fed

in much slower than others, such as hay, for instance, the feed rolls should be rotated at the rate of 5 rotations per minute in handling oats and up to 35 rotations a minute in handling some kinds of hay, and other materials 55 usually operated on by these mills will require, for best results, a wide range of speeds between these two extremes. The above extremes, however, are mentioned merely by way of illustration of the point and with no 60 intention to limit myself thereto.

In the present application I have shown and described the preferred form of my invention simply by way of the illustration of 65 the practice of my invention as by law required. However, I realize that my said invention is capable of other and different embodiments and that the various details thereof may be modified in various ways, all without departing from my said invention. 70 Therefore, the drawing and description herein are to be considered as merely illustrative, and not as exclusive.

In the accompanying drawings:

Figure 1 represents a side elevation of a 75 feed mill embodying my invention;

Figure 2, a front elevation thereof;

Figure 3, a sectional view on line 3—3 of Fig. 2 looking in the direction of the arrows 80 and omitting all parts of the casing except bar 30 and also pulley G and drive belt F; and

Figure 4, a sectional view on line 4—4 of Fig. 3, looking in the direction of the arrows 85 and omitting bar 30.

Referring now in detail to the drawings, A designates the mill casing and frame, B the feed table, hopper, trough or chute in which material is placed to be fed to the machine by means of usual feed rolls, not shown, mounted respectively on the shafts 27 and 29 inside of the casing to turn with said shafts, C represents the main drive shaft mounted in the casing and on which the hammer-rotor is mounted to turn therewith, said shaft C 90 having a pulley D on one end to be driven by a belt, not shown, from a suitable power plant, not shown, and having a pulley E mounted on its other end to turn therewith 95 and driving a belt F to drive pulley G mount- 100

ed on the end of shaft 1 to turn therewith, said shaft 1 and companion parallel shaft 16 being mounted in bearings carried by heavy vertical supporting reinforcing bars or beams 5 H secured in proper aligned position the front portions of the respective sides of the casing A, the construction thus far referred to being usual conventional construction in this art.

10 A pinion 2 having relatively long axially extending thin walled sleeves 2' extending in opposite directions from its radially extending medial peripherally toothed portion is mounted on said shaft 1 to have sliding movement axially thereof for, in the embodiment illustrated, practically the entire length of said shaft between its supporting bearings and is interlocked therewith by a long key or spline 3 to turn therewith in all positions 15 of said pinion 2 axially of the shaft 1.

15 A casing 7 is mounted by its upper end for partial rotation or swinging movement about said pinion 2 and its sleeves 2' and to this end has its upper end formed with oppositely 20 extending axial sleeves 7" in which are arranged suitable anti-friction, such as Babbitt metal, bearings 4 of the proper internal diameter to receive and cooperate with the respective sleeves 2' of said pinion 2, as illustrated in Figure 4. Said long sleeves 2' serve 25 to guard against possible canting of the pinion 2 as it is moved axially of the shaft 1 to the desired position of adjustment, and also serve as an efficient convenient means on 30 which to mount the upper end of the casing 7 for swinging movement. Said casing 7 may be comprised of two plate members fitting together in a direction axial of shaft 1, as shown in Fig. 4, and said plates may be 35 secured together by screws or suitable fastening means 9 passing transversely through lapping fins extending in lapping engagement from the opposed adjacent portions of the plates, or by welding, or by both means 40 and may be secured together at any convenient points and at as many points as may be desired or considered necessary.

45 In said casing are mounted for rotation two pinions 5 and 6 preferably respectively 50 integral with their shafts, which shafts are suitably supported in bearings in said opposed plates forming said casing. Said pinion 5 is at all times in mesh with pinion 2 mounted on shaft 1 and with pinion 6, as illustrated in Figure 3. Said pinions 2, 5 and 6 constitute a train of gears driven by shaft 1, the end pinion 6 of such train rotating in 55 the same direction as shaft 1 and selectively engaging any one of the gear wheels a, b, c, d, e, f, g, h, i and j all keyed to shaft 16 by key or long spline 17 and held with their adjacent axial faces in engagement and against movement axially of said shaft 16 by suitable stop means or collars 16' respectively arranged at opposite ends of such composite

60 gear cone and welded to or otherwise suitably held against axial movement on shaft 16.

65 A pinion 18 mounted on one end portion of shaft 16 serves to drive a chain 19 passing 70 about a sprocket or drive wheel 20 mounted on the corresponding end portion of a shaft 21 to turn therewith to drive said shaft. A smaller sprocket or drive wheel 22 mounted 75 on said shaft 21 to turn therewith and located thereon between sprocket or drive wheel 20 and the adjacent side of the casing A serves to drive a long drive chain 23 which passes about suitable idlers 24 and 25 to keep the chain taut and in driving engagement about 80 and between pinions 26 and 28 which are respectively mounted on the end portions to turn therewith of the respective feed roll shafts 27 and 29.

85 The relative diameters of the pulleys E and G, and sprocket or chain drive wheels 18, 20, 22, 26 and 28, and the length of chain 23 will be so calculated as, in a general way, to 90 reduce the speed of rotation of the feed roll shafts 27 and 29, which rotate in the direction 95 of the arrows to the desired point with relation to the speed of rotation of the hammer rotor so that this reduced speed of the feed rolls may be used as the starting point for 100 further selective variation of the speed of 105 said rolls within wide limits considering now the speed of said feed rolls as distinguished from the speed of the rotor.

105 In the embodiment illustrated I have shown ten gears a to j inclusive mounted on shaft 16 100 to turn therewith and of regular progressively increasing diameter from a to j, the relation 110 between the rest of the drive mechanism and the gears or pinions 2, 5 and 6 being such that when the gear or pinion 6 is in driving mesh 115 with gear j the shaft 16 will be driven at such speed as to drive the pinions 26 and 28 and their respective feed roll shafts at only 5 rotations per minute, whereas when the pinion 6 is in driving mesh with pinion or gear 120 a it will drive the shaft 16 at a seven times greater speed to cause the rotation of said pinions 26 and 28 and their respective feed roll shafts 27 and 29 at 35 rotations per minute, the gears b, c, d, e, f, g, h and i being 125 regularly progressively of different diameters to provide a wide range of selective speeds 130 between these two extremes to suit working conditions as they vary in accordance with the material being operated upon and the power available.

135 Of course the gears could be so proportioned that the extreme slow speed would be less than 5 rotations per minute of the feed rolls, and so that their maximum speed of rotation would exceed 35 rotations per minute, with relation to a given speed of rotation of the main drive shaft C, and the number of gears keyed to the shaft 16 between 140

the two end gears may be more or less than as illustrated.

To provide for the easy and quick adjustment of the speed of the feed rolls without stopping or modifying the speed of the shaft 5 C and to prevent misalignment of the train of gears 2, 5 and 6 with the selected gear keyed to shaft 16, I provide a rack-bar 30, which may be secured to the members H to hold it firmly in position, as shown in Figure 10 2 and form the lower edge portion thereof with a series of notches a', b', c', d', e', f', g', h', i' and j', arranged in succession in the order stated and form a long finger or rib 8 on the casing 7. Said finger 8 is of such thickness as to make a snug fit in the respective notches to prevent its movement therein axially of the shaft 1 when engaged in any one of said notches, and of such length transversely of the shaft 1 that the casing 7 must be partially 20 rotated about said shaft 1 and pinion 2 to a point where the adjacent portion of pinion 6 will lie at a greater distance from the axis of the shaft 16 than the peripheral outer faces of the teeth of gear wheel j, which is the gear-wheel of greatest diameter on the shaft 16. When the casing 7 has been swung upward about shaft 1 and pinion 2 to this point, that is, to neutral position, the finger or rib 8 will 30 have been partially rotated with said casing about its axis so as to lie inward and clear of the rack 30. The gear casing 7 with the pinion 2 may then be moved axially of shaft 1 to the desired notch and corresponding gear, and then a downward swinging movement 35 of the casing 7 will serve to turn the finger 8 in the reverse direction to fit into the notch of the selected gear, to prevent any axial movement of said casing and gear or pinion 2 relative to shaft 1 and the composite cone of gears. Continued downward swinging movement of the casing 7 will move the pinion 6 into driving mesh with the gear selected. For instance, if the slowest speed of the feed 40 rolls is desired, the casing 7 will be swung upward until in neutral position, as above described, and then will be moved axially of shaft 1, causing pinion 2 to slide axially with it, until the rib or finger 8 is opposite notch j', at which time the pinion 6 will be in registry with gear j, when the casing 7 will be 45 swung down, as above described, until the pinion 6 meshes with gear j, the finger or rib 8 turning into the notch j' as above explained and preventing misalignment and relative axial movement. If the highest speed of rotation of the feed rolls is desired the casing 50 7 will be manipulated as above described so that the finger or rib 8 is located in slot or notch a' and pinion 6 is in mesh with gear a. If any one of the intermediate speeds is desired, the casing will be manipulated as above described so that as finally adjusted the finger or rib 8 is located in one of the notches b', c', 55 d', e', f', g', h' or i' and the pinion 6 in mesh 60 d', e', f', g', h' or i' and the pinion 6 in mesh

with the corresponding gear of the gears b, c, d, e, f, g, h and i respectively.

To facilitate the manipulation of the casing 7 I provide the same with a handle or hand-grip 31. For holding the casing 7 down so as to maintain the pinion 6 in proper driving mesh with the gear a, b, c, d, e, f, g, h, i or j with which it may be selectively engaged, I provide means adjustable in the direction of the axis of the shafts 1 and 16 and adjustable toward and from the same and cooperating with means for locking the same and said casing against relative movement in a transverse plane perpendicular to the axes of said shafts in any one of the selective operative positions of said casing 7. Such hold-down means comprises a straight rod 12 adapted to be gripped and clamped against a portion of the casing 7, for instance the handle 31 thereof, by a hooked or clamping member 10. Said member 10 has a screw-threaded stem passing through said portion of said casing 8 and receiving a nut having an operative lever or arm 11 whereby said nut may be turned on said stem to draw the hook or clamping portion 10 thereof into tight frictional locking engagement with the rod 12. The upper end of said rod 12 may be offset as shown to provide a stop for the upward swinging movement of the casing and the rod may be of such length that when the casing 7 is swung up to neutral position, as above described it will be in contact with said stop, so that the movement to neutral position may be made quickly and with complete assurance with no need to closely observe the position of the finger or rib 8 with relation to the bar 30. The lower end of said rod 12 will preferably be formed into the eye 13 loosely fitting about a rod 14 suitably held in the arms of a bracket 15 secured to the front beam I of the two base supporting beams I, or otherwise suitably rigidly mounted in proper position with relation to the casing 7 and cooperating parts.

From the foregoing it will be seen that the eye 13 of the rod 12 can slide axially of the rod or bar 14 in accordance with the axial movement and adjusted position of the casing 7, and that said rod 12 may swing about said bar 14 as may be necessary during the swinging movement of said casing 7.

The upper feed roll with its shaft 27 and pinion 26 will preferably be mounted for movement toward and from the lower feed roll while continuing to be driven by chain 23 to allow the feeding in of corn-cobs and other relatively thick objects without interrupting the feeding operation and without impairing their efficiency to also feed in smaller material, this being usual practice and not forming part of my present invention and thus not being illustrated.

Any suitable materials may be used for any of the parts.

Having thus described my invention, what I claim as new and desire to secure by United States Letters Patent is:

1. A selective speed gear mechanism comprising a drive shaft, a drive pinion slidably mounted thereon to turn therewith, a driven shaft, and a plurality of gears of different diameters, mounted thereon to turn therewith, in combination with a casing mounted on said drive pinion for swinging movement about the axis thereof and movable therewith axially of said drive shaft, a plurality of pinions mounted for intermeshing engagement in said casing and driven by said drive pinion, said casing being movable to cause one of said plurality of pinions to mesh with any selected one of said plurality of gears to drive the same, a gripping element carried by said casing, a bar extending parallel to and in fixed relation with, said shafts, a rod mounted on said bar for free swinging movement about the axis thereof and free for sliding movement axially thereof and extending through said gripping means, and means for causing said gripping element to bind on said rod to hold said casing against swinging movement about said drive pinion.
2. A selective speed gear mechanism comprising a driving shaft, a drive pinion slidably mounted thereon to turn therewith, a driven shaft, and plurality of gears of different diameters mounted thereon to turn therewith, in combination with a casing mounted on said drive pinion for swinging movement about the axis thereof and movable therewith axially of said drive shaft, a plurality of pinions mounted for intermeshing engagement in said casing and driven by said drive pinion, said casing being movable to cause one of said plurality of pinions to mesh with any selected one of said plurality of gears to drive the same, a gripping element carried by said casing, a rod anchored by its lower end portion against upward movement in the direction of its length and swingable in a direction transverse of said shafts and free to move bodily with said casing and drive pinion axially of said drive shaft and having slidably engagement in said gripping means, and means for causing said gripping means to bind on said rod to hold said casing against swinging movement about said drive pinion.

In testimony whereof, I have signed my name to this specification at Lancaster, Pennsylvania this 27th day of October, 1928.

ABRAHAM M. DELLINGER.
